UNITED STATES PATENT OFFICE.

HARRY FORD, OF UTOXETER, ENGLAND.

VALVE OF INTERNAL-COMBUSTION ENGINES.

1,177,612.

Specification of Letters Patent.

Patented Apr. 4, 1916.

Application filed October 21, 1909, Serial No. 523,785. Renewed February 23, 1912. Serial No. 679,495.

To all whom it may concern:

Be it known that I, HARRY FORD, of Brookside House, Uttoxeter, Staffordshire, England, have invented Improvements in and Relating to the Valves of Internal-Combustion Engines, of which the following is the specification.

This invention relates to improved means for effecting distribution of the working fluid in an internal combustion engine.

The object of my invention is to provide means for effecting the inlet and exhaust of the working charge which shall be completely silent, simple of construction, and efficient in action.

Broadly, my improved means consists of a metal ring of suitable diameter, provided with teeth, fitted in or upon the wall of the combustion chamber in such a manner, that when caused to rotate, the port provided in the said ring registers with ports provided in the said wall at such a suitable time in the cycle as shall effect proper distribution. I construct the said ring preferably of cylindrical form and of sufficient thickness not to be warped or distorted by unequal heating or expansion.

I provide an annular chamber or channel, a portion of which may be formed in the cylinder cover, and a portion in the top of the cylinder casting, so that when the cover is bolted in position, the upper part of the annular chamber exactly registers with the lower, and the said chamber surrounds the combustion chamber. Or the said chamber may be wholly formed in either the cylinder casting or in the cover. Into this annular chamber, I fit the said ring, the said ring being as accurate and close a fit as possible consistent with its easy rotation or revolution within the said chamber. The axis of rotation of the said ring is preferably coincident with the axis of the cylinder. The said annular chamber is water jacketed, said water jacket also immediately surrounding the combustion and expansion chambers. Packing rings preferably of the piston type may be provided to prevent leakage of the gases. These may be fitted in suitable positions in the ring itself, or in the chamber so as to bear upon the ring. Or in a fitted stationary ring provided to support the said packing. Ball or roller bearings may be provided to take the weight of the ring and reduce friction, or alternatively the ring of a suitable metal such as cast iron, may bear

on the cast iron surfaces of the annular chamber.

I provide gear or teeth in a suitable position on the outside of the ring, or on the top or bottom edge of the ring if it be cylindrical, and by means of the properly proportioned teeth, in a four stroke cycle engine the ring is driven at half the speed of the engine. Thus the ring is continuously rotated by means of mechanism driven by the crank shaft. I may drive the said ring by ordinary skew gear from the crank shaft, the other end of the half speed side shaft being provided with a pinion; a portion of which projects inwardly in a suitable position and gears with the said teeth on the said ring. The ring may however, be rotated by any suitable means. I provide a port in the said ring which in a four stroke cycle engine is of such length, that it is adapted to register with a similar port in the cylinder wall for inlet of the charge, for about one fourth of its rotation. There are two ports provided in the cylinder walls, the one for inlet, the other for exhaust, and in a four stroke cycle engine one port only in the ring. The single port may however be divided into a series of apertures or ports.

The inlet and exhaust ports in a four stroke cycle engine are close to each other with only about the width of the ring port between them. Thus when the piston makes its out or suction stroke, the ring port registers with the inlet port in the cylinder wall for one fourth of its rotation, the ports are closed during the compression and explosion strokes and just before the end of the working stroke, the ring port registers with the exhaust port, and it is kept open for one fourth or slightly more of the rotation of the ring. And in order that my invention may be completely understood reference should be made to the appended sheets of drawings.

Figure 1 is a sectional elevation of the engine, on the line Y—Z of Fig. 3, but with the ports shown of full diameter as though it were a section in one plane for the sake of clearness. Fig. 2 is an elevation. Fig. 3 is a plan of the top of the cylinder with the cover removed. Fig. 4 is a part section of a constructional modification. Fig. 5 is an elevation of the ring.

Like letters of reference refer to like parts in each figure.

A is the cylinder, B the piston, C the

cover, D the crankshaft, E is the ring, F is a horizontal side shaft parallel with the crank shaft, driven by the chain and sprocket wheels indicated in Fig. 2. The 5 shaft drives the vertical side shaft G by means of the bevel gear wheels F¹ G¹ (Fig. 1) the former being indicated by dotted lines. On the top of the shaft G the pinion H is secured. The pinion H gears with 10 the tooth formed in the upper peripheral edge of the ring E, as shown in Figs. 1, 3, 4 and 5. The ring E is driven by the pinion at half the speed of the crank shaft by means of the shaft G, bevel wheels G¹, F¹, 15 shaft F and the chain and sprocket before referred to. The wheel H is inclosed in an air tight casing H¹ having air tight joints to prevent leakage of oil or gases.

The ring E, (Fig. 5) is provided with the 20 single port E¹. The ring is fitted in the annular chamber E² which is surrounded by the water jacket. In the cylinder cover C is the inlet port I, shown in Fig. 1.

J is the exhaust port.

25 The ring E is rotated by the gear wheel H in the direction of the arrow Fig. 3, and the distance between the inlet port I and the exhaust port J being only slightly greater than the circumferential length of the port

30 E¹ in the ring E, it follows that very shortly after the exhaust port is closed by the ring, the port E¹ begins to open the inlet port I, as is required by the four stroke cycle. During the compression and explosion strokes, 35 the port E¹ is moving away from the port I in the direction of the arrow, until at the end of the working stroke, the port J commences to open again.

In Fig. 1 are shown removable two L 40 shaped rings L M in each of which are fitted two packing rings of the ordinary type. The two rings L M are spigoted or lipped together at the joint in order to prevent leakage. At the top and bottom respectively of the ring E is a ring of balls fitting in a grooved ring or ball race provided in the rings L and M. But neither the packing rings nor the ball race is essential to the invention.

45 As one modification or varied constructional form the arrangement Fig. 4 is shown in which the rings L M and the ball races are dispensed with, and the ring E fits the annular channel E² with as little friction as possible, and packing rings are fitted as shown, on the outer cylindrical surface, of the ring E.

S S are sparking plugs and W is a carbureter.

50 It will be obvious that the shaft G may be rotated directly by the crank shaft at the required speed in accordance with the relative number of teeth on the ring E and the pinion H, and this might be conveniently done either by bevel gear or skew gear or

in other known manner, it being of course essential that with the four stroke cycle the ring E shall make one revolution for every two revolutions of the crank shaft. If the valve ring E be employed for engines of the two stroke cycle then it must have the same 70 number of revolutions as the crank shaft.

I claim—

1. In an internal combustion engine, a cylinder, an annular valve casing externally of the cylinder and in communication therewith through separate admission and exhaust ports and passages, an annular valve in the valve casing for controlling the communication between the valve chamber and the cylinder, said valve having teeth thereon, a pinion engaging the teeth, and means for rotating the pinion. 75

2. In an internal combustion engine, a cylinder having separate admission and exhaust ports, a piston in said cylinder, a shaft, means connecting said piston and said shaft, a valve casing encircling the cylinder, a cylindrical valve in and filling the casing for controlling said ports, packing 80 between the valve and the internal wall of the valve casing on opposite sides of said ports, and means for rotating the valve. 85

3. In combination, an internal combustion engine having separate inlet and exhaust ports, with a ported sleeve acting as a valve and controlling the inlet and exhaust ports of the engine, said engine being formed with an annular valve casing in which said sleeve is contained and also having inlet and exhaust passages opening through the outer wall of said casing and also controlled by said sleeve, and a gear operating in an opening in said casing and rotating said sleeve in time with the movements of the engine piston. 95 100

4. In combination, an internal combustion engine having lateral inlet and exhaust ports, with a ported sleeve acting as a valve and controlling the inlet and exhaust ports of the engine, said engine being formed with an annular valve casing intersected by the engine ports and in which said sleeve is contained and lubricated, packing means preventing the flow of lubricant from said 110 casing into said engine ports, and means operating in an opening in the side of said casing and rotating said sleeve in time with the movements of the engine piston. 115

5. In combination, an internal combustion engine having separate lateral inlet and exhaust ports, with a ported sleeve acting as a valve and controlling the inlet and exhaust ports of the engine, said engine being formed with an annular valve casing intersected by said ports and in which said sleeve is contained and lubricated, the outer 120 wall of said casing containing corresponding separate inlet and exhaust passages also controlled by said valve, a gear on said 125 130

sleeve and within said casing, and a driving gear meshing therewith and whereby said sleeve is rotated in time with the movements of the engine piston.

6. In combination, an internal combustion engine having separate lateral inlet and exhaust ports, with a ported sleeve acting as a valve and controlling the inlet and exhaust ports of the engine, said engine being formed with an annular valve casing intersected by said ports and in which said sleeve is contained and lubricated, the outer walls of said casing containing corresponding inlet and exhaust passages also controlled by said sleeve, packing means making tight the compression space of the engine cylinder and preventing the flow of lubricant from said casing into said ports, a gear on said sleeve and within said casing, and a driving gear meshing therewith and whereby said sleeve is rotated in time with the movements of the engine piston.

7. In an internal combustion engine, a cylinder in combination with a piston operable therein, a removable head closing the outer end of the cylinder forming a closed annular valve chamber surrounding the cylinder, separate admission and exhaust ports

connecting the chamber and cylinder, a ring valve in the chamber controlling said ports and means operatively connecting the valve and the piston.

8. In an internal combustion engine a cylinder and piston in combination with a cylinder head concentric with the cylinder and fixed therein, the head and adjacent cylinder wall coöperating to form a concentric valve chamber closed at its inner end, the head and cylinder walls being provided with coöperating admission and exhaust passages entering said chamber between its ends, an annular rotatable valve in said chamber having a port arranged between its ends adapted to register with said passages for controlling the admission and exhaust of gases to and from the cylinder and a valve actuator operable by the piston adapted to constantly rotate the valve in one direction to control the opening and closing of the passages in proper time with the movements of the piston.

HARRY FORD.
